UNITED STATES PATENT OFFICE.

WILLIAM DOWNIE, OF SAN FRANCISCO, CALIFORNIA.

WATER-HEATING COIL FOR GAS-PLATES.

1,109,117.

Specification of Letters Patent.

Patented Sept. 1, 1914.

Application filed November 4, 1912. Serial No. 729,495.

To all whom it may concern:

Be it known that I, WILLIAM DOWNIE, a citizen of the United States, residing in the city and county of San Francisco, State of California, have invented a new and useful Improvement in Water-Heating Coils for Gas-Plates, of which the following is a specification.

My invention relates to water heating coils for gas plates wherein a coil is retained within suitable openings provided within the spider or radial arms that are provided on the gas plate for the support of the utensil that it is desired to heat, and its objects 15 are, first, to provide simple and effective means for heating water from the flame that is being used for cooking purposes on a gas plate, and second, to provide simple and effective means for retaining the coil above 20 the burner in such a manner that the said coil will not prevent the heat from reaching the bottom of the cooking utensil on the spider or radial arms.

For a full comprehension of my invention, 25 reference should be had to the accompanying drawings forming a part of this specification in which—

Figure 1 is a plan view of a gas plate with my device applied thereto. Fig. 2 is a vertical section taken on line X—X of Fig. 1. The numeral 1 is used to designate the frame of a gas plate having radial arms 2 provided in the upper edges thereof with the semicircular openings 2'. A frame 3, adapted 35 to coincide with the upper surface of the frame 1, having radial arms 4 with semicircular openings 4' in the lower edges thereof rests on the top of the frame 1 in such a manner that the openings 2' and 4' coincide 40 and form circular openings or apertures in which the coil 5, for the circulation of the water to be heated, is retained. One end of the coil is turned downwardly through the central opening in the circular burner 7 and 45 the other end is turned downwardly between the radial arms 2 and 4 and then turned toward the back of the frame 1. The ends

may be connected to the boiler or water supply in any suitable manner.

After the top frame 3 has been removed 50 the coil 5 may be easily lifted from the openings 2' after having been disconnected from the boiler and water supply.

It is obvious from the foregoing that I 55 have provided simple and effective means for supporting a water heating coil on a gas plate in a manner that will expose the said coil to the heat of the burner without preventing the heat from reaching the bottom of the cooking utensil.

The details of the construction are so susceptible to variation that I do not wish to confine myself to the precise construction shown herein but rather to avail myself of any modifications that may fall properly 65 within the scope of my invention.

Having thus described my invention what I claim as new and desire to secure by Letters Patent is—

1. In a water heating coil for gas plates, 70 the combination of a suitable gas plate having radial arms with semicircular openings in the upper edges thereof; a water heating coil adapted to engage the semicircular openings; and means for retaining the coil 75 within the said semicircular openings.

2. In a water heating coil for gas plates, the combination of a suitable gas plate having radial arms with semicircular openings in the upper edges thereof; a water heating 80 coil within the semicircular openings; and a superimposed plate having radial arms with openings in the lower edges thereof and adapted to coincide with the radial arms and 85 openings therein of the gas plate and to retain the water heating coil between the gas plate and the superimposed plate.

In witness whereof I hereunto set my signature in the presence of two subscribing witnesses.

WILLIAM DOWNIE.
